UNITED STATES PATENT OFFICE.

ROBERT GEORGE, OF MINERAL POINT, WISCONSIN.

IMPROVED FURNACE FOR ROASTING AND TREATING ORES.

Specification forming part of Letters Patent No. 80,065, dated July 21, 1868.

To all whom it may concern:

Be it known that I, ROBERT GEORGE, of Mineral Point, Iowa county, State of Wisconsin, have invented a new and improved furnace for oxidizing, chlorifying, desulphurizing, and disintegrating ores, metallurgical and chemical products; and I do hereby declare the following to be a full and exact description thereof, reference being had to the accompanying drawings and letters of reference marked thereon.

The nature of my invention consists in a furnace, fully described hereinafter, whereby the desulphurizing, chlorifying, and disintegrating ores, metallurgical and chemical products containing sulphur, arsenic, phosphorus, antimony, tellurium, and selenium are perfectly accomplished in larger quantities and in shorter time than heretofore has been the case, for the purpose of separating the precious metals from ores and metallurgical compounds, as well as for the freeing of the ores of the baser metals from injurious substances and the preparation of the alkalies from chlorides and alkaline combinations.

To enable others skilled in the art to make and use my invention, I will proceed to describe its construction and operation.

In reference to the accompanying drawings, which form a part of this specification, Sheet I, Figure 1 is a plan view on the line A B of my improved furnace for oxidizing, chlorifying, &c. Fig. 2 is a rear elevation. Sheet II, Fig. 3 is a longitudinal section on the line C D E F G H. Fig. 4 is a transverse section on the line I K L M N O. Sheet III, Fig. 5 is a longitudinal elevation. Fig. 6 is a front elevation.

The sectional lines are indicated by red lines and red-colored capital letters.

The different materials are denoted as follows: stone masonry, reddish-brown; common brick-work, pink; fire-clay work, yellow; iron, blue.

Similar letters in black ink refer to similar parts throughout the several elevations and sections.

My furnace consists of two oxidizing or disintegrating chambers, D and C. The requisite heat is generated in the fire-chamber A, with the door a, ash-pit B, and the door b for regulating the draft. The fire passes through the flues c¹ c² c³ c⁴ c⁵ into the oxidizing-chamber C, and finds

its exit through the flues q¹ q² q³ q⁴, while the oxidizing-chamber D is heated by the products of combustion passing through the flues d¹ d² d³ d⁴ d⁵ into D finding their vent through the chimney E into the atmosphere. The S-orifice serves to regulate the fire for the two oxidizing-chambers C and D by means of the damper M and M² over the main flue c¹ and d¹.

If it is desirable to conduct all the heat generated in the fire-chamber to the oxidizing-furnace C, the damper M² is to be closed, and also the dampers e in the chimney E, while the dampers e on the rear part of the furnace D are to be opened and the products of the combustion will pass through the oxidizing-chamber D, generating in the same a less degree of heat, as may be desired by the nature of the materials to be oxidized or chlorified. The products of combustion in this case will pass off through the chimney F.

In order to facilitate the process of desulphurizing and disintegrating of the ores and products under treatment, and to prevent the fusion of the same or the formation of sulphates thereof, a requisite quantity of water is to be let into the furnace and converted into steam in the following manner: Pipe K is connected with a tank of water of a certain height, feeding the pipes m¹ and m². The valves n¹ n² n³ are to regulate the influx of the water into the n⁴ siphons o¹ o² o³ o⁴, through which the water passes into the pipes p¹ p² p³ p⁴ and trickles in a heated state into the pipes G¹ G², &c., where it becomes converted into steam, which passes into the clay-pipes G² G³ and G⁴ G⁵ and finds its exit at the orifices k k¹, &c., and k k², &c., in the highest degree possible of superheated steam. The heat necessary for this purpose is procured from the fire through the flue j¹, j², and l, passing directly from the fire-chamber through j¹ into the tube-chamber H, thence under the tubes G¹ G² G³, and thence into the flue l¹, heating the pipes p¹ p², entering the flue q¹, and finally in chimney E. A similar course takes place from l into the tube-chamber H³, while the fire from flue j² passes through H² into l², also the fire from l² through H⁴ into l², finding its vent through the flue q⁴ into the chimney E. The orifices t¹ and t² serve to regulate the heat in the flues j¹ and j² and l¹ and l² by brick dampers. The temperature of the superheated steam in tube G³, which passes through a connection-tube into G⁴ and G⁵, is in

these pipes to the highest degree possible intensified by the fire of the main flue c^2 and c^3 being properly distributed by the orifices k' , &c., passing immediately over the flues for the products of combustion c^4 , mingling with the latter by entering through the flues c^5 into the oxidizing-chamber O. In a similar manner is the superheating of the steam effected in the tubes to be placed in chamber H³, which tubes are connected by G⁶ with G⁷ and G⁸, finding its exit in the orifices k^2 and k^3 , having intermingled with the products of combustion issued by d^4 entering into the oxidizing-chamber D. The conversion of the water into steam, its superheating, and introduction into the oxidizing-chambers C and D are accomplished from pipes p^3 and p^4 in a similar manner on the opposite side of the furnace.

The unusual high degree of temperature of the superheated steam could practically only be accomplished by substituting fire-proof tubes instead of iron pipes, because the intense heat necessary for this purpose would give the iron the degree of heat at which water decomposes this metal, converting it into an oxide, and in this way rendering it unfit for this purpose.

It is further a fact that by heating fire-clay or porcelain tubes a strong electric current is generated in the interior, and I have discovered by experimenting that it electrifies (ozonizes) the superheated steam in such a manner that the oxidization and disintegration of the mineral substances above named are much more effectively accomplished than by any process heretofore known. It may be further seen that by this process of injecting water instead of steam the quantity of the water can more easily be controlled by inexperienced hands than if it were in the form of steam. It can be checked at pleasure without any danger of explosion. It saves the purchasing and separate running of a steam-boiler, keeping it in repair, and transporting it in destitute mountainous regions, where often great expense is required to build new roads for such purpose and repairs are very difficult to be effected and wages for experienced laborers quite high. The several parts of my apparatus are of trifling weight, great duration, and can easily be replaced without the necessity of stopping the furnace for any length of time.

The charging and discharging of the desulphurizing-furnace is carried on in the following manner: The materials to be treated may be charged through the opening f into the oxidizing-chamber D, in which they will be spread by the stirring-machine L, which will be specially described hereinafter. If the nature of the materials under treatment in this oxidizing-chamber requires a higher degree of heat for their perfect disintegration—as, for instance, a mixture of those materials whose components decompose water by different degrees of heat, as is the case with alkalies, alkaline earths, iron pyrites, copper pyrites, &c.—the materials in chamber D may be dis-

charged through openings g' and g^2 into the disintegrating-chamber O for their perfect decomposition, after which they may be removed without molestation to the laborers through the openings h' and h^2 . If it is desirable, however, to keep the materials of the chamber D separate from those of the chamber O, the same may be removed by the doors r^3 and r^4 . The same doors, as well as the doors r' and r^2 , serve the laborer to control the treatment of the materials and the proper working of the stirring-machine in the respective disintegrating-chambers.

The stirring-machine L consists of three leading-pipes, $x^1 x^2 x^3$, which are fastened in the sockets of pipes $i' i i^2 i^3$. In the latter are the pipes $u' u^2 u^3 u^4$, rectangularly inverted in such a manner that they may turn in the same. The pipes $u' u^2 u^3 u^4$ serve for the alternate connection of the stirring-shoes $c' c^1$, &c., and $c c^2$, &c., which is effected by slides or loops $k k$, holding the top end of the stirring-shoe $c c$, &c., to the hollow exit-pipes $j j'$ or $j j^2$, which project from the main pipes $u' u^2 u^3 u^4$. The shoes are kept steady by means of set-screws $d d$ at a requisite distance from the floor of the furnace. The stirring-machine is held together by the stationary rods $v' v^2 v^3 v^4$, $l l'$ and $l l^2$. On the pipe $i i'$ is a car-wheel, $f f'$, and on pipe $i i^2$ a similar wheel, $f f^2$, is fastened in such a manner that the same can easily be replaced when repairing demands it. The wheels revolve either on iron bars or on brick-work. On the front of the furnace are concave friction-rollers $y' y^2$, &c., fastened to keep the machine in its proper position and to facilitate its motion. The stirring-machine moves from one end of the oxidizing-chambers to the other. The motive power is derived by connecting the machine in a convenient manner with steam, water, or horse power.

The materials to be disintegrated are agitated in the following manner: By the motion of the stirring-machine from the front to the rear of the furnace the materials in the furnace are placed up in furrows by the reverse motion of the machine, the particles of the materials on the surface of the previously-formed furrows are turned under, while the inward substance becomes exposed on the surface of the newly-forming furrow, so that a perfect contact of the oxidizing or disintegrating substances is effected, and avoiding at the same time a continuous motion, as is the case in a rotary apparatus, of all material particles, which consequently would disturb, or at least retard, the decomposition of the different materials to be disintegrated. The stirring-shoes are set in a plowing position by the levers $a a$ and $b b$. When the machine arrives at the front end of the oxidizing-chamber the lever $a a$ will strike the interior wall of the furnace and place the shoes in a working position, while by means of the coupling-rod $m m$ the lever $b b$ is turned so far as to lift the stirring-shoes $c c'$ on the pipes u^3 and u^4 above the materials under treatment till the lever strikes

the rear wall of the furnace and turns the shoes in a reverse position.

The object for constructing the leading parts of the machine, $x' x^2 x^3$, $u' u^2 u^3$, and $u' u^2 u^4$, and the exit-pipes $j j$ hollow is for the double purpose to cool the machine in the fire, as well as guard against a want of oxygen in the oxidizing-chambers. By this means air, steam, or water, separately or together, enter through the injections $z' z^2 z^3$ on the pipes $x' x^2 x^3$, which pass through the machine. Air or steam finds its exit at the projections $j j$ immediately to the agitated materials, while when water is used for the cooling of the machine it will pass off either by a separately inverted pipe or a partition in the pipes $x' x^2 x^3$ $u' u^2 u^3 u^4$ through $z' z^2 z^3$, while the exit-pipes $f f$ are closed.

On the rod v^3 and v^4 there are attached two scrapers, w' and w^2 . These scrapers are, during the process of disintegration, suspended on hooks $o o'$ and $o o^2$. When the materials are to be discharged the scrapers are set in working position, and will carry the disintegrated materials by every movement of the machine from rear to front, while during the motion of the machine to the rear of the furnace the scrapers are turned over by the joint $n n$, and uplifted by the wheels $p p$, carry no materials backward, so that the same are accumulated only on the front of the furnace, and thence they may be withdrawn with ease by the laborer, either through the door r' and r^2 and r^3 and r^4 , or, as above stated, from chamber D through the openings g' and g^2 into the chamber C, and from there through h into the arched room $g g'$ and $g g^2$. Here they may remain to cool off till they are removed at pleasure for the purpose above stated.

If the furnace is to be worked for chlorifying silver ores for the purpose of their perfect amalgamation, which ores do not often contain the requisite quantity of sulphurets or sulphates absolutely necessary to secure a per-

fect disintegration, or if the furnace is to be worked for the purpose of producing alkaline sulphates from chlorides, refuse from salt-works, or alkaline earths, the necessary quantity of sulphurous acid may easily be produced as a by-product, when the oxidizing-chamber C is charged with sulphuret ores or metallurgical products for the subsequent purpose of extracting therefrom the precious metals, or to render the baser metals more valuable, or for both purposes combined. The silver ores or the alkaline matters are then to be charged into the disintegrating-chamber D, in which the sulphurous acid or sulphuric acid produced in the chamber C is conducted by keeping the dampers $i i$, &c., in the chimney E closed, while the flues $e e$, &c., are opened for the exit of the surplus products of combustion through the chimney F.

What I claim as my invention, and desire to secure by Letters Patent, is,—

1. An oxidizing, desulphurizing, chlorifying, and disintegrating furnace, as shown in the drawings and detailed in the specification.
2. A stirring-machine, with all its parts, as illustrated and specified.
3. A water and heating apparatus, as illustrated, and for the purpose described.
4. The substitution of fire-clay or porcelain tubes, or their equivalents, for the purpose of converting water into steam and superheating the same.
5. The cooling of the stirring-machine by air, steam, or water, used separately or combined, in the manner and for the purpose as described and set forth.

In testimony whereof I have signed my name to this specification in the presence of two subscribing witnesses.

ROBERT GEORGE.
